DRILL CHIP BREAKER

Erik Hallden, Detroit, Mich., assignor to Ex-Cell-O Corporation, Detroit, Mich., a corporation of Michigan

Application May 15, 1947, Serial No. 748,263

7 Claims. (Cl. 77—33)

1

The invention relates to drill chip breakers generally and more particularly to an improved chip breaker of the type adapted to be incorporated in the rotary drive for a drill and operative to alternately exert an axial thrust on the drill and to relieve it during its rotation for the purpose of severing previously formed chip curls.

One object of the invention is to provide a drill chip breaker characterized by the simplicity of its construction, its small size, and by the small number of parts subject to wear.

Another object is to provide a drill chip breaker having very low internal frictional resistance whereby heating of the breaker is reduced sufficiently to eliminate the need for the elaborate heat dissipating construction heretofore required.

A further object is to provide a drill chip breaker having antifriction bearing means adapted to absorb the axial thrust imposed on the tool and operative automatically to alternately project and relieve the tool supporting member as an incident to its rotation.

Other objects and advantages of the invention will become apparent from the following detailed description of the preferred embodiment illustrated in the accompanying drawings, in which:

Fig. 1 is a side view of a drill chip breaker embodying the features of the invention.

Fig. 2 is a top view of the chip breaker.

Fig. 3 is a longitudinal sectional view of the chip breaker taken in a horizontal plane substantially on the line 3—3 of Fig. 2.

Fig. 4 is a transverse sectional view of the chip breaker taken in a horizontal plane substantially on the line 4—4 of Fig. 3.

Fig. 5 is a transverse sectional view of the chip breaker taken in a horizontal plane substantially on the line 5—5 of Fig. 3.

Fig. 6 is a diagrammatic view showing the positions of the bearing elements relative to the bearing track in the relieved position of the tool.

Fig. 7 is a sectional view taken in intersecting planes as indicated by the lines 7—7 of Fig. 6.

Fig. 8 is a diagrammatic view similar to Fig. 6, but showing the positions of the bearing elements upon rotation of the bearing element retainer through an angle of ninety degrees.

Fig. 9 is a sectional view taken in intersecting planes as indicated by the lines 9—9 of Fig. 8.

While the invention is susceptible of various modifications and alternative constructions, I have shown in the drawings and will herein describe in detail the preferred embodiment, but it is to be understood that I do not thereby intend

2

to limit the invention to the specific form disclosed, but intend to cover all modifications and alternative constructions falling within the spirit and scope of the invention as expressed in the appended claims.

Referring more particularly to the drawings, the drill chip breaker selected to illustrate the invention comprises a casing 10 having a hollow cylindrical body section 11 with an inturned annular flange 12 at one end. A flanged cover section 13 is removably secured to the other end of the body section, as by screws 14. Extending through a central opening 15 in the cover section 13 is a rotary driving member 16 adapted to be connected with and supported from a spindle or quill 17 of the transmission head of a machine tool. The driving member 16 is maintained in assembled relation with the casing 10 by a circumferential flange 18 engaging in an annular recess 19 formed in the inner face of the cover member 13. An arm 20 rigid with and projecting radially from the casing 10 is adapted to engage a stationary abutment (not shown) to hold the casing stationary when the driving member 16 is rotated.

Extending through the opening defined by the flange 12 of the casing 10 is a driven member 21 adapted to support a rotary cutting tool, such as a drill 22 in axial relation. The outer or projecting end of the member may be of any preferred construction depending upon the manner in which the tool 22 is to be supported. As herein shown, the member 21 is formed with a tapered socket 23 for receiving the complementally tapered shank of the tool. A transverse slot 24 at the base of the socket is provided for the reception of a diametrical tang 25 formed on the end of the tool shank, whereby the tool is non-rotatably anchored to the member 21. The driven member 21 is retained in assembled relation with the casing 10 by a circumferential flange 26 formed thereon and adapted to seat against the inner face of the flange 12.

The driving and driven members 16 and 21 are aligned axially and are interconnected within the casing 10 for rotation as a unit and for relative axial movement. To this end one of the members, in this instance the driving member 16, is formed with a diametrical tang 30, herein shown as a generally cylindrical axial extension which is flattened at opposite sides. The adjacent end of the companion or driven member 21 is formed with an axial recess 31 complemental in cross section to the tang 30 and adapted to receive the latter with a sliding fit.

In accordance with the invention, antifriction bearing means is provided within the casing 10 for transmitting the axial thrust of the driving member 16 to the casing and from the casing to the driven member 21, and operative automatically as an incident to the rotation of the members to alternately project the driven member axially away from the driving member and then relieve the driven member to permit it to return to its initial position. More particularly, the arrangement of the bearing means is such that as the tool is fed to the work by a uniform feeding movement of the spindle 17, the bearing means is effective during a portion of each revolution of the tool to exert an outward thrust on the driven member 21, causing the tool to advance at a slightly faster rate than the feeding rate of the spindle. In the succeeding portion of the revolution, the outward thrust on the driven member 21 is relieved to permit a momentary dwell or to reduce the rate of advance of the tool sufficiently to sever the chip curl formed by the tool during the preceding portion of its revolution.

In the present embodiment of the invention, the bearing means comprises an annular bearing plate 35 disposed between the flanges 18 and 26 of the driving and driven members and encircling the upper end of the driven member. The bearing plate is nonrotatably secured in the casing in any suitable manner, as by screws 36 passing through the cover section 13. The axial thrust of the driving member 16 is transmitted to the bearing plate 35 through a series of bearing elements, herein shown as balls 37 retained in a suitable cage 38 and adapted to coact with complementary annular bearing races 39 and 40 formed respectively on the lower face of the flange 18 and the upper face of the bearing plate 35.

Interposed between the bearing plate 35 and the flange 26 of the driven member 21 is an antifriction bearing unit 41 comprising an annular cage or retainer 42 having a series of circumferentially spaced pockets for the bearing elements, preferably ball bearings. In the particular embodiment illustrated, the cage 42 is arranged to hold four ball elements uniformly spaced apart circumferentially of the race to insure a balanced thrust on the driven member at all times.

To provide the intermittent thrust and relief for enabling the drill to break the chip curls formed in its action on the work, the plate 35 is formed with a bearing track 45 presenting an undulating surface for the travel of the ball elements of the bearing unit. As herein shown, the bearing track 45 comprises a continuous shallow groove arcuate in cross section and defining an ellipse symmetrical with the rotational axis of the cage 42. Due to the elliptic shape of the track 45 the ball elements of the unit 41 alternately ride up and down the sides of the groove as the cage 42 is rotated relative to the plate 35.

In order to insure a balanced thrust on the driven member 21 and to distribute the wear uniformly over both sides of the track groove 45, the ball elements of the bearing 41 on opposite sides of the axis of the bearing are arranged to traverse paths of different diameters. Thus, the ball elements 41 forming one opposed pair are spaced apart so as to traverse a circular path A and the ball elements 48 forming the other opposed pair are spaced apart so as to traverse a circular path B of smaller diameter than the

path A, as shown in Figs. 6 and 8. To properly relate the track 45 with respect to the paths of the ball elements, the track is formed with a major axis x corresponding in length to the diameter of the larger path A and with a minor axis y corresponding in length to the diameter of the smaller path B.

By reason of the particular relationship of the track 45 to the paths A and B of the ball elements, as above described, all four ball elements will be positioned so as to rest in the bottom of the track groove when the bearing plate 35 and the bearing cage 42 are positioned so that the balls 47 are alined on the major axis x of the track and the ball elements 48 on the minor axis y thereof, as shown in Figs. 6 and 7. As the cage 42 is rotated relative to the plate 35, the ball elements 47 ride up the outer side of the track groove, while the ball elements 48 ride up the inner side of the groove and reach the upper edge thereof when the cage has turned through an angle of ninety degrees to the position shown in Figs. 8 and 9. In their movements between the above two positions, the ball elements are effective to project the driven element 21 axially outward from the driving element 16 and thus increase the feed imparted by the spindle 17 by an amount equal to the depth of the track groove 45.

In the succeeding ninety degrees of rotation of the cage 42 relative to the bearing plate, the ball elements 47 and 48 ride down the sides of the track groove until the parts again reach the positions shown in Figs. 6 and 7 with the ball elements resting in the bottom of the groove. In such movement the tool is relieved either interrupting its advance completely or reducing it substantially, depending upon the feed rate of the spindle 17 and the rotative speed of the same. In either case, the change in the rate of advance is such as to cause the drill to sever the chip curls formed in the preceding ninety degrees of rotation of the bearing cage.

Since the bearing cage 42 is rotated as a result of the rolling of the ball elements 47 and 48 around their respective paths, it will be evident that the cage turns through a half revolution for each full revolution of the driven member 21. As explained above, each half revolution of the cage is effective to project and relieve the tool as the ball elements 47 and 48 travel from the bottom to the top edge of the track groove and then back to the bottom of the groove. Accordingly, the tool will be projected and relieved once in each full revolution, thus effectually preventing the formation of long chip curls which might interfere with the efficient operation of the drill.

To reduce wear on the bearing elements 47 and 48 and on the parts with which they coact, the elements are graduated in size according to their distance from the rotational axis of the cage 42. Thus, in the exemplary embodiment the outer bearing elements 47 are substantially greater in diameter than the inner bearing elements 48, the diameters being such that each of the elements travels over its cooperating bearing surfaces with a true rolling action. To compensate for the different diameters of the two elements, the inner face of the flange 26 is formed with a stepped surface providing one annular bearing race 49 for the ball elements 47 and a second bearing race 50 spaced inwardly therefrom for the ball elements 48.

It will be apparent from the foregoing that the invention provides a drill chip breaker of novel

and advantageous construction. The novel bearing arrangement provided in the chip breaker reduces internal friction to a minimum, while operating automatically to alternately project and relieve the tool so as to break the chip curls formed thereby. The use of ball elements materially reduces wear on the parts of the tool and the novel arrangement and relationship of the elements effectually insures against excessive wear of the elements themselves. In general, the improved chip breaker is very simple in construction and small in size, yet efficient and reliable in operation.

I claim as my invention:

1. A drill chip breaker comprising, in combination, a casing, driving and driven members disposed coaxially in said casing and projecting at opposite ends thereof, said driven member being operative to support a drill in axially projecting relation thereto, cooperating means on said members connecting them for rotation as a unit and permitting relative axial movement therebetween, means on said members forming opposed axially facing bearing surfaces, an annular bearing plate supported in said casing and extending between said bearing surfaces, antifriction bearings interposed between the bearing surface of said driving member and the adjacent face of said plate, two pairs of ball elements interposed between the bearing surface of said driven member and the adjacent face of said plate, a cage adapted to hold the ball elements of each pair on diametrically opposite sides of said driven member with the ball elements of one pair located midway between the ball elements of the other pair and traversing a circular path of greater diameter than the path traversed by the ball elements of said other pair in the rotation of said retainer, a shallow groove in the face of said plate engaged by said ball elements and forming an elliptic track for the elements symmetric with the rotational axis of the driven member, said track having a major axis corresponding to the diameter of the path traversed by said one pair of ball elements and a minor axis corresponding to the diameter of the path traversed by the other pair of ball elements whereby said ball elements are adapted to move alternately from the bottom of the groove to the edge thereof and back again as said retainer rotates.

2. A drill chip breaker comprising, in combination, a casing, driving and driven members disposed coaxially in said casing and projecting at opposite ends thereof, said driven member being operative to support a drill in axially projecting relation thereto, cooperating means on said members connecting them for rotation as a unit and permitting relative axial movement therebetween, means on said members forming opposed axially facing bearing surfaces, an annular bearing plate supported in said casing and extending between said bearing surfaces, antifriction bearings interposed between the bearing surface of said driving member and the adjacent face of said plate, two pairs of ball elements interposed between the bearing surface of said driven member and the adjacent face of said plate, a cage adapted to hold the ball elements of each pair on diametrically opposite sides of said driven member with the ball elements of one pair located midway between the ball elements of the other pair and traversing a circular path of greater diameter than the path traversed by the ball elements of said other pair in the rotation of said retainer, a

shallow groove in the face of said plate engaged by said ball elements and forming an elliptic track for the elements symmetric with the rotational axis of the driven member, said track having its major and minor axes dimensioned so that said ball elements move upwardly from the bottom of the groove to the edges thereof and then back to the bottom of the groove in the rotation of the retainer through a half revolution, said ball elements acting in such movement to project the driven member axially away from the driving member and then permit retraction of the driven member to its initial position.

3. A drill chip breaker comprising, in combination, a casing, driving and driven members disposed coaxially in said casing and projecting at opposite ends thereof, said driven member being operative to support a drill in axially projecting relation thereto, cooperating means on said members connecting them for rotation as a unit and permitting relative axial movement therebetween, means on said members forming opposed axially facing bearing surfaces, an annular bearing plate supported in said casing and extending between said bearing surfaces, antifriction bearings interposed between the bearing surface of said driving member and the adjacent face of said plate, two pairs of ball elements interposed between the bearing surface of said driven member and the adjacent face of said plate, a cage adapted to hold the ball elements of each pair on diametrically opposite sides of said driven member with the ball elements of one pair located midway between the ball elements of the other pair and traversing a circular path of greater diameter than the path traversed by the ball elements of said other pair in the rotation of said retainer, a shallow groove in the face of said plate engaged by said ball elements and forming an elliptic track for the elements symmetric with the rotational axis of the driven member, said track having its major and minor axes dimensioned so that said ball elements rest in the bottom of said groove in one position of the retainer and ride up opposite sides of the groove to the edge thereof as the retainer is rotated through an angle of ninety degrees relative to said bearing plate whereby the driven member is projected axially away from the driving member.

4. A drill chip breaker comprising, in combination, a casing having openings in opposite ends, a driving member rotatably supported in the casing and projecting through the opening in one end thereof, a driven member rotatably supported in the casing and projecting through the opening in the other end thereof, said driving and driven members being axially aligned and having cooperating elements connecting them for rotation as a unit while permitting relative axial movement therebetween, a bearing member fixed in said casing and having in one face a shallow groove forming a continuous elliptic bearing race, said bearing member being disposed in said casing with said groove facing said other end of the same and with the axis of the groove symmetrical with the rotational axis of said driven member, a circumferential flange on said driven member defining an annular bearing race spaced from and opposed to the grooved face of said bearing member, a series of ball elements interposed between said flange and said bearing member, and a cage operative to hold said ball elements in predetermined spaced relation to the axis of said driven member whereby in the rotation of the

member the ball elements alternately ride up and down the sides of said groove to exert an axial thrust on said driven member and to relieve said thrust whereby to permit inward axial movement of the driven member.

5. A drill chip breaker comprising, in combination, a casing having openings in opposite ends, a driving member rotatably supported in and projecting from the opening at one end of the casing, a driven member for axially supporting a drill rotatably supported in and projecting from the opening at the other end of the casing, said members being connected for rotation as a unit and for relative axial movement, a circumferential flange on said driven member defining an inwardly facing bearing surface, a bearing member mounted in said casing with one face in opposed relation to said bearing surface, said member having a groove in said one face forming an elliptic track symmetrical with the axis of said driven member, two pairs of ball elements interposed between said member and said bearing surface, said ball elements being arranged with the respective elements of each pair diametrically disposed at opposite sides of said driven member, the spacing of the elements of one pair corresponding to the major axis of said elliptic track and the spacing of the elements of the other pair corresponding to the minor axis of said elliptic track, and means for maintaining the ball elements in said spaced relation in the rotation of said driven member.

6. A drill chip breaker comprising, in combination, a casing, a driving member rotatably supported in and projecting from one end of the casing, a driven member rotatably supported in and projecting from the other end of the casing, cooperating means on said members connecting them for rotation as a unit and permitting relative axial movement therebetween, a circumferential flange on said driven member defining inwardly facing concentric bearing races spaced apart axially of the driven member, a bearing plate mounted in said casing with one face disposed in opposed relation to said bearing races,

a first set of ball elements interposed between one of said bearing races and said plate, a second set of ball elements interposed between the other of said bearing races and said plate, said one face of said plate being grooved to form an elliptic track symmetrical with the axis of said driven member and having a major axis corresponding to the diameter of the path travelled by the ball elements of said first set and a minor axis corresponding to the diameter of the path travelled by the ball elements of said second set, and a retainer for maintaining the spacing of said ball elements in the rotation of said driven element.

7. A drill chip breaker comprising, in combination, driving and driven members supported in axial relation and interconnected for rotation as a unit and for relative axial movement, said driven member having an inwardly facing bearing surface, a fixed bearing member having one face disposed in opposed relation to said bearing surface, said one face of said member being formed with a shallow, noncircular groove symmetrical with the rotational axis of said members and constituting a bearing track, a plurality of groups of ball elements interposed between said bearing surface and said bearing member for cooperation with said track to alternately project and relieve said driven member axially with respect to said driving member, and a cage operative to constrain said groups of ball elements to circular paths corresponding respectively to the major and minor dimensions of said track whereby to distribute the wear over different portions of said bearing surface and the groove forming said track.
